UNITED STATES PATENT OFFICE

WILLIAM L. BARRON, OF LAURENCE HARBOR, NEW JERSEY, ASSIGNOR TO THE SINGER MANUFACTURING COMPANY, OF ELIZABETH, NEW JERSEY, A CORPORATION OF NEW JERSEY

BOBBIN-THREAD TENSION-DEVICE FOR SEWING MACHINES

Application filed July 29, 1931. Serial No. 553,863.

This invention relates to bobbin-thread tension-devices for sewing machines and more particularly to such devices for sewing machines having a circularly moving loop-taker or shuttle within the field of which is supported a thread-case for a wound mass or bobbin of thread.

In the use of a sewing machine for certain ornamental stitching and embroidering operations, it is necessary to run the bobbin-thread under a heavier tension than is ordinarily required in regular straightaway sewing operations. For example, in embroidery cording or cord-covering operations, a heavy bobbin-thread tension is required to insure the proper tightness of the stitches around the cord or filler-thread used. In other cases, a heavy bobbin-thread tension is required to insure that the lock-points of the needle and bobbin-threads will not be drawn through to the upper or finished side of the work by the sewing machine take-up. Furthermore, it is often desirable to run these comparatively heavy tensions on very fine threads of, say 25 from .0025 to .005 inch in diameter.

It has been proposed to meet the requirements for embroidery work by increasing the thickness of the usual bobbin-thread tension spring but this has proven unsatisfactory as 30 the increased thickness so stiffened the spring that it would not readily permit the passage of lumps or irregularities in the bobbin-thread and would not impose a uniform tension on the thread with a satisfactory degree 35 of certainty. A slight increase or decrease in the size of the thread, for example, would cause a great variation in the tension and spoil the appearance of the work.

For other sewing operations a light bobbin- 40 or under-thread tension is required and where a heavy enough spring was used to meet embroidering requirements it was found impossible to adjust it to a light uniform tension on the thread desired for other sewing operations.

The present invention, therefore, has for an object to provide a bobbin-thread-case of the circular type with a tension-device having a wide range of adjustment to adapt the 50 machine for a great variety of sewing opera-

tions necessitating considerable variation in the thread-tension requirements for the bobbin-thread; a further object of the invention being to attain the desired range while maintaining uniformity of action of the device under any given adjustment. Still further, the invention has for an object to provide a bobbin-thread tension-device meeting these requirements while preserving a minimum working clearance between the thread-case and the loop-taker or shuttle.

To the attainment of the ends in view, the invention comprises the devices, combinations and arrangements of parts hereinafter described and claimed.

The features of the invention and the advantages attained thereby will be readily understood by those skilled in the art from the following detailed description of a preferred embodiment of the invention illustrated in the accompanying drawing, in which Fig. 1 is a front face elevation of a bobbin-thread-case embodying the invention. Figs. 2 and 3 are enlarged sectional views of the thread-case showing the tension-spring adjusted for light and heavy tension requirements, respectively. Fig. 4 is a top plan view of the thread-case in working position and Fig. 5 is a disassembled perspective view of the thread-case.

1 represents the usual sewing machine throat-plate having the needle-hole 2 and feed-dog slot 3. Disposed below the throat-plate 1 is the circularly moving loop-taker 4 illustrated in the form of the usual oscillatory shuttle having the raceway-bearing-rib 5, the loop-seizing beak 6 and the throat 7 and heel 8 which are engaged by the usual shuttle-driver (not shown). The shuttle is shown in one extreme position of its oscillatory motion, ready for its beak 6 to advance for seizure of a needle-loop.

Supported within the field action of the shuttle 4, upon the usual central thread-case supporting arbor 9 of the shuttle, is the 95 thread-case 10 in the form of a hollow circular shell having a central tubular arbor 11 adapted to support the usual wound bobbin 12 of under-thread 13.

The wall of the thread-case is formed with 100

a slot 14 in which is anchored the tail end 15 of the leaf tension-spring 16 which is made from flat spring stock bent to the curved form shown and hardened and set 5 to have an unsprung radius of curvature less than the radius of curvature of the outer surface of the thread-case. It is not to be understood that the unsprung curvature of the spring 16 is in the true arc of a circle 10 throughout its length. The point is that it is more sharply arched than the surface of the thread-case to which it is applied so that it tends to engage the surface of the thread-case at its extreme ends and is arched up 15 between its ends where it is formed with a clearance hole 17 for the tension-adjusting screw 18 threaded into the aperture 19 in the thread-case.

The end of the tension-spring 16 opposite 20 or remote from the tail end 15 is preferably formed to constitute a bobbin-thread delivery-guide; such end preferably having ear-portions 20 bent over upon the exposed or outer face of the thread-case and received 25 in the face-notch 21 in the thread-case; such ear-portions being preferably formed with or defining a thread-delivery aperture 22.

The bobbin-thread 13 leads from the bobbin 12 outwardly through the thread-aperture 23 to the outer surface of the 30 thread-case over which it runs under the spring 16 to the thread-guide 22 and is pressed upon by the spring 16 only at the point 24 considered circumferentially of the 35 thread-case, as shown in Figs. 2 and 3.

It will be observed that the extreme end 25 of the spring 16 is free of interference with the thread-case under all conditions of adjustment of the curvature or tension of the 40 spring 16 within the limits provided. This objectionable end-contact is avoided preferably by flattening the outer cylindrical surface of the thread-case, as at 26. The only point of thread-tension contact is definitely 45 fixed at the point of intersection 24 between the flat 26 and the outer circular wall of the thread-case, and remains fixed under all conditions of adjustment and variations in curvature of the spring 16 caused by its adjustment 50 without interference between the extreme end of the spring and the wall of the thread-case.

By virtue of the present improvement a 55 spring 16 of desired flexibility and strength may be so set or initially curved to gain the desired heavy tension when strained to the position of adjustment shown in Fig. 3, and still permit a uniform weak-tension to be attained by backing off the screw 18, Fig. 2, 60 without danger of interference with the pressure upon the thread by engagement of the extreme end 25 of the spring 16 with the thread-case. Thus, under all conditions of adjustment, the entire pressure of the tension-spring is applied to the thread at a

definite point, regardless of the degree of deformation or arching of the tension-spring caused by the adjusting screw 18. A spring of considerable flexibility may be used to good advantage, giving a wide range of tension adjustments with a high degree of uniformity of action for any given adjustment. 70

Having thus set forth the nature of the invention, what I claim herein is:—

1. A bobbin-thread-case having a circular shell and a thread-tension leaf-spring applied to the outer surface of said shell, said spring having an unsprung radius of curvature less than the radius of curvature of said surface, a tension-adjusting screw passing through 75 said spring between the ends of the latter and into said shell, the proximate surfaces of said spring and shell adjacent one end of said spring being shaped to provide a definite and fixed point of contact between the two circumferentially of the thread-case and within said end of said spring for any adjustment of the tension and curvature of said spring within the working limits provided, the extreme end of said spring adjacent said point of contact being free of interference with the thread-case under all conditions of adjustment. 80

2. A bobbin-thread-case having a circular shell and a thread-tension leaf-spring applied to the outer surface of said shell, said spring 85 having an unsprung radius of curvature less than the radius of curvature of said surface, a tension-adjusting screw passing through said spring between the ends of the latter and into said shell, the portion of the thread-case under one end of said spring being flattened to permit free tilting movement of said end and to prevent contact between said end and the thread-case for any adjustment of the tension and curvature of said spring within 90 the working limits provided. 100

In testimony whereof I have signed my name to this specification.

WILLIAM L. BARRON.
